PERFORATED RECORD SORTING MACHINE

Louis H. Fronefield, Binghamton, N. Y., assignor
to International Business Machines Corporation,
New York, N. Y., a corporation of New York

Application June 13, 1934, Serial No. 730,403

9 Claims. (Cl. 209—110)

This invention relates to perforated record sorting machines and more particularly to machines of this nature which are adapted to analyze a plurality of columns of perforations representing a plurality of numerals or other characters, during a single operation.

It is common in sorting machines of the present character, to run a stack of cards through the machine once for each digit in a number, in order to remove from the stack all of those cards containing a particular number. Or, if the cards are to be sorted into numerical or other order, a single column on the card is analyzed during each run through the machine and the cards are separated into several pockets in accordance with the digit represented by the perforation in the column being analyzed.

Statistical and other data cards are often numbered to represent a particular group to which they belong and if these cards are in a common stack containing cards of several groups, it is frequently necessary to remove from the stack, cards belonging to a particular group and to then sort the cards of this group into numerical or other order. If the group number contains three digits, it is necessary to run the cards through the machine three times to collect those belonging to the particular group and to then run these cards through the machine again to effect the proper arrangement of the cards of that group.

An object of the present invention is to provide a machine which will sort all of the cards of a particular group during a single run of the machine.

Another object is to sort out of a stack of cards, all those of the particular group as indicated by perforations in several columns, and at the same time, distribute them into the several pockets of the machine in accordance with data perforations contained in another column.

Referring to the drawings wherein I have shown what I now consider to be the preferred form of my invention:

Fig. 1 is a front elevation, partly in section, of a sorting machine;

Fig. 2 is a perspective view, partly in section, of certain parts of the sorting control elements;

Fig. 3 is a wiring diagram.

In the drawings, the sorting machine is shown as having several sorting pockets 1, into which the cards 2 are sorted. It is common in these machines to provide thirteen of these pockets as shown in United States Patent 1,880,428. These pockets correspond to the ten numerals 0-9, with two extra pockets known as the 11 and the 12

pockets, and one reject pocket to receive all cards not belonging to any of the twelve numbered pockets. The cards 2 are placed in a hopper 3 and are fed by a card picker 4, one at a time to feed rollers 5. The picker is connected to an arm 4a pivoted at 4b in a cushioned support 4c. A cam 4d fixed on a constantly running shaft 4e moves the parts to the left which is the card feeding stroke, while the springs 4f restore them to the right. The drive for the shaft 4e as well as for the feed rollers is omitted here as it is well known. The cards thus pass between sorting brushes 6 and an electric contact in the form of a conducting roller 7.

In the present machine, there are shown five sensing brushes 6 adapted to cooperate with five separate columns on the card. The brushes are mounted on a carriage 8 slidably mounted on a threaded rod 9 and are capable of being moved along this rod so as to cooperate with any desired columns on the card. Several of the brushes may be fixedly mounted with respect to each other, so as to sense a group of adjacent columns on any part of a card, while one of the brushes 6a, may be mounted separately from the others so that it may be set to analyze any other column.

As the card passes between the brushes and the contact roller, each brush cooperates with a single column on the card and is held out of contact with the roller 7 by the card, until a perforation in one of the index positions in the column reaches the sensing position. At such time, the brush reaches through the perforation and makes contact with the roller 7 to close an electric circuit through an electromagnet to control the operation of the machine in accordance with the particular index position in the column at which the perforation is located. After the card has been analyzed, it moves on as indicated in Fig. 2, carried by the additional feed rollers 5 and enters between the ends of chute blades 10 and is carried to one of the several pockets in accordance with the particular position between the blades that it occupies.

At the beginning of a sorting cycle in accordance with the aforesaid patent, all of the chute blades 10 are in raised position and as the first index point i. e., the "9" at the bottom of the card as shown in Fig. 2, passes under the sensing brush or brushes, one of the sorting blades is adapted to drop. As the next index position passes under the brush, a second chute blade drops and so on until all of the index positions in the column have passed under the sensing brush. If a per-

45

50

55

foration appears at one of these index positions, then a sorting circuit will be closed and will lock the chute blades in the particular position which they occupy at that time in the cycle, so that no 5 additional blades will drop and when the card arrives at the end of the blades, it will pass above all the blades which had dropped and below those which are held up. The path thus created for the card leads to the pocket corresponding to the 10 position of the perforation in the column analyzed.

In accordance with the present invention, instead of dropping the blades successively as the index points pass the sensing brushes, certain 15 control elements are unlatched but the blades continue to be held in their raised position until the end of the card sensing operation. Then, if the card belongs to the particular group desired, the blades are allowed to drop and the 20 card passes into the path thus created and is carried to the sorting pocket. But, if the card does not belong to the desired group then the blades are all held in their upper position and the card passes beneath them and is carried into 25 the first pocket which is the reject pocket.

The ends of the blades are normally held in raised position by individual supporting arms 11 which are pivoted at 12. Each arm 11 is held in its upper position by an individual latching 30 member 13 pivoted at 14 and is provided with a spring 15 tending to pull it downwardly when released. All of the latches 13 are held in latching position by a common bail 16. Also, all of the arms 11 are held up by a common restoring 35 ball 17 latched by the armature 18 and electromagnet 19. Corresponding to each of the latches 13 is a cam 20, all of which are fixed on a common axis or shaft 21 driven synchronously with the feeding mechanism so as to synchronize with 40 the passage of the successive index positions in the columns under the sensing brushes 6. The cams 20, at a common point in the cycle of the machine, all restore their respective latches 13 to latching position and then proceed to release 45 the latches successively as the successive index positions on the cards pass the brushes.

As each latch 13 is released by its cam, it will rock counterclockwise under the action of its spring 22, the bail 16 being in inoperative position as in Fig. 1. When a latch 13 releases its 50 arm 11, the latter continues to be held up by the common bail 17. The latches 13 are controlled by brush 6a. When a perforation passes under this brush, an electromagnet 23 will be energized, attracting its armature 24 to release the projection 25 of the bail 16 and permitting the spring 26 to raise the bail from the position of Fig. 1 to that of Fig. 2. The latches 13 that have been released by their cams 20 up to this 55 point in the cycle will then be in the position designated 13a in Fig. 2, while those that have not yet been released are latched in position as in Fig. 2 and cannot, during the remainder of the cycle, release their arms 11. If, after the 60 analyzing operation, magnet 19 is energized, the bail 11 will be released and will rock downwardly about its pivot 27, permitting all of the unlatched arms 11 to drop with their blades 10, while the arms 11 which are still latched will hold their 65 blades in raised position. This will determine the path between the blades for the entrance of the card.

Referring to Fig. 3, the brush 6a is connected to a brush 28 which cooperates with a conductor ring 29 on a commutator member 30. Sev-

eral individual contact segments 31, also carried by the member 30, are all connected electrically to the ring 29 and make contact successively with a brush 32. The segments 31 correspond to the index positions in the column on the card. As 5 each index position is passing under the brush 6a a corresponding one of the segments 31 is passing under the brush 32. If a perforation appears at one of the index positions, the brush 6a will reach through and make contact with the roller 10 7 and close a circuit through the magnet 23 as follows: from the positive side of the line 33, to the common brush 34, roller 7, brush 6a, brush 28, ring 29, a particular segment 31, brush 32, electromagnet 23, back to the other side of the 15 line 35.

The energization of the magnet 23 at a time in the cycle, depending upon location of the perforation, thus serves to lock the latches 13, some in holding and some in releasing position with 20 respect to their arms 11.

At the same time that the brush 6a is analyzing its particular column on the card, one or more of the other brushes 6b etc., are also analyzing other columns on the card. These other columns may contain perforations representing a group number. And where all the cards of a particular number are wanted, a setting will be effected by which only those particular cards will control the operation of the electromagnet 19. 30 Assuming that the group control number contains three digits, then three of the sensing brushes designated 6b, 6c, and 6d will be employed while the brush 6e will not be used in controlling the sorting. Each of these additional 35 sensing brushes is connected to a brush 36b, 36c, etc., cooperating with a ring 37b, 37c, etc., on a commutator member 38b, 38c, etc. Associated with each of the rings 37b, 37c, etc., is a row of contact segments 39, each segment corresponding to one of the index point positions in the columns sensed by the respective brushes 6b, 6c, etc. The rows of segments 39 cooperate with brushes 40b, etc., whereby the segments pass the latter successively and synchronously with the 45 sensing of the index point positions in the card by brushes 6b, 6c, etc. Any segment 39 in each row may be made current conducting with respect to the associated rings 37b, 37c, etc., by some simple means as a movable arm 41. By turning 50 each arm 41 to bring it into contact with any one of the segments 39, that particular segment will be electrically connected through the brush 36 to the brush 6b, etc., at the time in the cycle when the desired index point in the 55 particular column cooperates with the brush 6b.

Assuming that the group control number in the present instance is 214, then the arm 41 will be moved into cooperation with the segment 39 on the commutator member 38b associated with the brush 6b, i. e., the brush of the tens order. The brush 6c of the hundreds order will in like manner be connected through the particular segment 39 corresponding to the 7 index position on the card by moving the arm 41 to the appropriate position. In like manner, the brush 6d of the thousands order is connected through the particular segment 39 corresponding to the index position 2 of its column on the card by a setting of its commutator arm 41. The brush 6e of the tens of thousands order is to remain inactive and its corresponding arm 41 will be set in normal or inoperative position and this particular brush will be cut out of operation by the closing of a switch 42e. Corresponding 70 75

switches 42b, 42c, 42d are set in open position as indicated. A brush 40b is connected to an electromagnet 43b which is adapted to operate two armatures 44b and 45b. The commutators 30 and 38b, 38c, etc., may all be carried on the common shaft 21 so as to operate synchronously with the rest of the analyzing elements of the machine. Assuming now that the card which is passing under the analyzing brushes has a perforation at the index position 4 in the column with which brush 6b is cooperating, the perforation will reach the brush 6b at the same time that the segment 39 on which the arm 41 is set reaches brush 40b. This will cause a circuit 15 through electromagnet 43b as follows: from the line 33, through brush 34, roller 7, brush 6b, brush 36b, arm 41, segment 39 on which the arm 41 is set, brush 40b, electromagnet 43b, through contacts 46 which are closed during the analyzing 20 portion of the cycle, to the other side of the line 35.

Magnet 43b, upon attracting its armatures 44b, 45b, closes contacts 47b, 48b, so that as the perforation passes from under the brush 6b and 25 breaks the circuit through magnet 43b, the armatures will continue to be held in their set position to maintain the contacts 47b and 48b closed, through electromagnet 49b. The circuit through magnet 49b is from the line 33, wire 50, magnet 30 49b, contacts 47b, through armature 48b, contacts 46 to the line 35. This then holds the contacts 48b closed. If there is a perforation at the index position 7 in the hundreds column which brush 6c is analyzing, a circuit will be set up 35 through electromagnet 43c in the same manner in which magnet 43b was energized, and will close contacts 47c and 48c. Similarly, if a perforation appears in the 2 index position in the column associated with brush 6d then a similar 40 circuit will be established through electromagnet 43d to close contacts 47d and 48d. Contacts 48e will not be affected as the brush 6e is not controlling.

Thus, if the group number 274 appears in the 45 card which is being analyzed, a circuit will be closed through the magnet 19 from the line 33, through switch 42e, contacts 48d, 48c, 48b all of which were closed as we have seen, through magnet 19 to the other side of the line 35. This 50 magnet as shown in Fig. 2 releases the bail 17 so that those arms 11 which have been released by their latches 13 can drop with their chute blades 10 while the arms 11 which are still held by latches 13 remain in the upper position.

55 Thus, a card of the group number 274 will pass into the path between blades 10 created by the brush 6a which is analyzing the units or other column, and the card will be conducted into one of the several pockets depending upon 60 which index position in such column is perforated. If the card does not contain the group number 274, then one or more of the contacts 48b, 48c, 48d will not be closed and no circuit will be closed through magnet 19 so that the 65 latter will not release the bail 17 and none of the chute blades 10 will be lowered and the card will pass into the reject pocket R.

After the card has entered the path created 70 between the ends of the chute blades, the cam 51 which has held the contacts closed, permits them to open. This breaks the circuit through the magnets 49b, 49c etc., and the associated contacts 47b, 48b, 47c, 48c, etc., will open, and these parts will be in restored position ready for the 75 next sorting cycle. Cam 51 may be carried by

shaft 21. At this same restoring portion of the cycle the chute blades and associated parts are also restored. The bail 17 has a cam follower arm 17a which is actuated by a cam 17b on shaft 21 to raise all of the arms 11 and the chute blades 5 10. Following the restoration of arms 11, the raised portion 20a of cams 20 will restore all of the latches 13 to position, latching the arms 11. The portions 20a on all of the cams 20 are in alignment and act at the same time. But just 10 before this takes place, the bail 16 is restored by a follower arm 16a, actuated by a cam 16b on shaft 21.

While there has been shown and described and pointed out the fundamental novel features of 15 the invention as applied to a single embodiment it will be understood that various omissions and substitutions and changes in the form and details of the device illustrated and in its operation may be made by those skilled in the art 20 without departing from the spirit of the invention. It is the intention, therefore, to be limited only as indicated by the scope of the following claims.

What is claimed is:

1. In a sorting machine, a series of sorting pockets, a series of sorting blades each leading to a pocket for guiding records into said pockets, means for analyzing successively presented record cards, means to operate the blades, means 30 to initially select the blades for operation, means controlled by the analyzing means for controlling the selecting means in accordance with designations in the records, and means controlled by the analyzing means for causing the blade operating means to operate in accordance with the selection made by the selecting means only on the occurrence of predetermined designations in the records. 35

2. In a sorting machine, a series of sorting 40 pockets, a series of record guiding elements each leading to one of said pockets, means controlled by designations in successively presented records for preliminarily selecting the guide elements for operation, and means controlled only by predetermined designations in said records for causing the blades to operate in accordance with the preliminary selection made by the selecting means. 45

3. In a perforated card controlled sorting machine, a plurality of guide blades for controlling the distribution of cards, means for holding said blades in normal position, a latch for each of said holding means, a plurality of cams for controlling said latches to successively release said 50 holding means, means controlled by a perforation in a column on a card for further controlling said latches, a common latch normally latching all of said holding means, and additional means controlled by perforations in a plurality of other 55 columns on a card for controlling said common latch.

4. In a sorting machine, record sensing means, a series of sorting pockets, a series of sorting blades extending from the pockets to a common 60 sorting station, means at the sorting station and controlled by the sensing means for preselecting the blades for operation under control of a designation in a record at the sorting station, and means controlled by the analyzing means for 65 causing the sorting blades to operate in accordance with the pre-selection only on the occurrence of predetermined designations in the records. 70

5. In a sorting machine, record analyzing 75

- means, a series of sorting pockets, a series of sorting blades leading from a common sorting station to the respective pockets, means at the sorting station for selectively operating the blades including blade pre-selecting means and means controlled by the analyzing means for causing the pre-selecting means to operate in accordance with designations in the records, and means at the sorting station controlled by the analyzing means for causing the blades to be operated by the operating means under control of the pre-selecting means only on the occurrence of pre-determined designations in the records.
6. In a sorting machine, record analyzing means, a series of sorting pockets, a series of sorting blades leading from a sorting station to the respective pockets, means at said station to pre-select the blades for operation including a single magnet controlled by the analyzing means for controlling the pre-selecting means in accordance with the value of any one of a plurality of different designations in a record, and means at said station for operating the blades under control of the pre-selecting means including a second magnet controlled by the analyzing means in accordance with only predetermined designations in the records.
7. In a sorting machine, a series of sorting blades, a series of latches each for holding one of said blades in a normal position, means common to all said blades for preventing them from

responding to release of the latches, means for successively releasing the latches, means controlled by designations in successively presented records for selectively interrupting release of the latches, and means controlled only by predetermined designations for operating the common means to permit operation of the unlatched blades.

8. In a sorting machine, a series of sorting blades, means to pre-select the blades for subsequent operation, a record analyzing device, means controlled by part of the analyzing device for causing the pre-selecting means to operate in accordance with a data designation in a record analyzed, means to prevent operation of the blades in accordance with the pre-selection effected by the pre-selecting means, and means controlled by a different designation through the analyzing device for rendering the preventing means ineffective.

9. In a sorting machine, a series of sorting blades, means to normally prevent operation of the blades, record controlled means for operating the sorting blades including means to pre-select the blades for operation, and supplemental record controlled means for releasing the preventing means to permit operation of the blades in accordance with the pre-selection only on the occurrence of records having predetermined designations.

LOUIS H. FRONEFIELD.
